(No Model.)

M. C. PLUMMER & O. O. DINSMORE.
AUTOMATIC DOOR OPENER.

No. 511,455.

Patented Dec. 26, 1893.

UNITED STATES PATENT OFFICE.

MICAJAH C. PLUMMER AND ORIN O. DINSMORE, OF PARALTA, IOWA; SAID DINSMORE ASSIGNOR TO SAID PLUMMER.

AUTOMATIC DOOR-OPENER.

SPECIFICATION forming part of Letters Patent No. 511,455, dated December 26, 1893.

Application filed April 27, 1893. Serial No. 472,120. (No model.)

To all whom it may concern:

Be it known that we, MICAJAH C. PLUMMER and ORIN O. DINSMORE, citizens of the United States, residing at Paralta, in the county of Linn and State of Iowa, have invented a new and useful Automatic Door-Opener, of which the following is a specification.

This invention relates to an automatic door-opener adapted for single or double doors, and has for its object to improve devices of this class and to adapt the same for use in hotel dining rooms where waiters have to pass through with their hands full, or in other similar places to provide means for conveniently opening the door or doors.

With this and other objects in view, the invention consists of the construction and arrangement of the parts thereof as will be hereinafter more fully described and claimed.

In the drawings: Figure 1 is a perspective view of a door and adjacent part of the framework, embodying the invention and showing the door partially open in dotted lines. Fig. 2 is a transverse vertical section. Fig. 3 is a detail perspective view of the operating platform, looking toward the bottom thereof. Fig. 4 is a detail view showing the arm of the rock-shaft engaging the headed stud or pin of the door.

Similar numerals of reference indicate corresponding parts in the several figures of the drawings.

Referring to the drawings, the numeral 1 designates a suitable frame, to which is hinged a door 2, that may be provided with suitable weather stripping 3, and has the lower edge at the rear formed with a recess 4, from which vertically depends a headed stud or pin 5. The door 2 is hung high enough to permit the mounting or positioning of a platform 6 thereunder that stands at a very slight elevation above the level of the floor and comprises a long section 7, to which is hinged a shorter section 8, both of said sections running to an elevated point at or about the center thereof on an upward incline. The hinges connecting the parts of the platform comprise a pair of metallic straps 9, on each side that engage each other and connected by a rod or pintle 10, the inner opposing edges of the said sec-

tions 7 and 8 being suitably recessed or grooved to permit the free passage and location of the said rod or pintle 10. At the inner edge of the section 7, on the underside of the same, is secured a metal plate 11, having a pair of downwardly-extending arms 12, that are spaced apart from each other, and the adjacent under edge of the section 8 has a wear-plate 13 secured thereto. The arms 12 project downwardly into a metallic well 14, located under the door and have a pair of transverse shafts or rods 15 carrying shouldered dogs 16, that extend downwardly into the well and are properly positioned relatively to the latter. The said dogs are united to operate simultaneously by a rod 17, that is movably connected to the same and whose one end is projected toward the rear and attached to a crank 18, of a vertically-disposed crank-shaft 19, that has bearing against the side of the well 14, as at 20. The upper end of the crank-shaft projects above the surface of the well and has a horizontally-disposed arm 21, with a shouldered or hooked end 22, said arm normally occupying a position in the recess 4 of the door and the shouldered or hooked end thereof engages the headed stud or pin 5, to thereby impart the movement to open the door to the latter against the resisting action of a suitable spring 23, having one end connected to the frame 1 and the opposite end attached to said door.

It will be seen that the hinge connection of the two sections of the platform 6 provides for the free movement of one section of said platform on the other when the section 7, especially, is depressed by weight brought to bear thereon. When the platform entire is in position the arms 12 rest in the shouldered portions of the dogs 16, and the latter being normally elevated within the well 14, hold the center of the platform elevated. When the platform 7 is depressed by a person walking upwardly thereon the arms 12 are forced downwardly, and thereby move the dogs 16 down into the well 14 and draw on the rod 17, which pulling on the crank 18 will operate the crank-shaft 19 to throw the arm 21 rearward and thereby force the door open. After the person has passed through the door-opening, the latter will automatically close be-

cause the weight or pressure is removed from the platform section 7, as it will be seen that the section 8 merely serves to obviate the formation of an abrupt fall on the opposite side of the door. When the door closes the pin or stud 5 presses forwardly on the arm 21, and thereby the crank-shaft 19 forces the rod 17 and the dogs 16 back to their normal position. In addition to the purpose of the section 8 of the platform, as already stated, the same also, through its connection with the section 7, operates to keep the door open when a weight is brought to bear thereon long enough to permit a person to pass through the door-opening.

Changes in the form, proportion, and the minor details of construction may be resorted to without departing from the principle or sacrificing any of the advantages of this invention.

Having described this invention, what is claimed as new is—

1. In a door-opening mechanism, the combination of a door having a headed stud or pin depending therefrom, an arm adapted to engage said headed stud or pin, a crank-shaft secured to said arm, a rod attached to the crank-shaft, a pair of shouldered dogs connected to said rod and mounted upon shafts, and a platform comprising two hinged sec-

tions elevated at the center and one of which is supplied with depending arms removably engaging the said shouldered dogs, the said door being supplied with a closing spring, substantially as described.

2. In a door-opening mechanism, the combination of a door having a closing spring in connection therewith, and a depending headed stud or pin, a horizontally disposed arm engaging said headed stud or pin, a crank-shaft vertically disposed and having said arm secured to the upper end thereof, a rod connected to said crank-shaft, a pair of shafts extending transversely under the door upon which shouldered dogs are mounted that are connected to the said rod, a platform composed of two hinged sections elevated at their meeting connected ends, and a plate connected to one of said sections and having a pair of depending arms that are spaced apart and loosely engage the said shouldered dogs, substantially as described.

In testimony that we claim the foregoing as our own we have hereto affixed our signatures in the presence of two witnesses.

MICAJAH C. PLUMMER.
ORIN O. DINSMORE.
